VACUUM TUBE OSCILLATOR SYSTEM

Montford Morrison, Upper Montclair, N. J.

Application November 5, 1948, Serial No. 58,510

5 Claims. (Cl. 250—36)

1

The present invention relates generally to electron discharge tube oscillators, in particular to systems of feed-back in such oscillators, and more specifically to the employment of multiple feed-back systems to a single tank circuit.

This application is a continuation in part of application Serial No. 1,595, filed January 10, 1948.

Among the objects of the invention are: to provide an oscillator which may operate at a frequency having a degree of freedom independent of the natural period of the controlling tank circuit; to provide an oscillator which may operate over a wide range of frequencies with a fixed LC in the controlling tank circuit; to provide an oscillator which may operate at the maximum degree of controlling-tank-circuit apparatus efficiency for any character of oscillator load; to provide an oscillator which may operate at the maximum degree of controlling-tank-circuit electrical efficiency for any character of oscillator load; to provide an oscillator with an indirect inductive reactance stabilized feed-back; to provide an oscillator with a direct condensive reactance stabilized feed-back; to provide multiple feed-back circuits of different reactive characters, permitting variation in oscillator frequency performance with fixed LC in the tank control circuit; and various and other objects which will be pointed out and obvious to those skilled in the art to which the invention appertains, upon reading the specification hereunder, in connection with the accompanying drawings.

The nature of the invention resides importantly in the employment of oscillator structure and method of oscillator operation, which depends upon a novel discovery in oscillator functioning, or at least in a novel combination of underlying theories, not heretofore collectively consolidated into a working explanation of oscillator operation.

It is believed that in order to give a full, clear and exact description of the invention, it will be necessary to provide a fuller, clearer and more exact theory of oscillator operation, as applied to the present invention, than is known to the applicant in published texts. The applicant will provide herein such extra-conventional theory as is thought to be pertinent.

The invention will be more fully understood from the following description and extra-conventional theory, when read in connection with the accompanying drawings, of which:

Fig. 1 is a diagram illustrating the method employed by the applicant to determine the

2

phase angle between the voltage and the current, the figure of merit "Q," the resonant frequency, the frequency of the natural period or free period, and the frequency under equal reactance or equal susceptance operation, of a tank circuit when referred to herein.

Fig. 2 shows graphs illustrating some of the operation of Fig. 1.

Fig. 3 shows a particular oscillator operating under condensive loading and Figs. 4 and 5 are other oscillator circuits which are used in illustrating the extra-conventional theory given herein;

Figs. 6, 7 and 8 are graphs relating to the oscillators shown in Figs. 3, 4, and 5; and

Fig. 9 is a diagram illustrating the methods of making tests which define certain terms used in the extra-conventional theory presented herein.

Figs. 10 and 12 are simple circuits illustrating and correcting some of the fragmentary theory vectorically represented in Figs. 11 and 13 of the prior art, not heretofore associated with oscillator operation.

Fig. 14 is a diagram of an oscillator circuit having a degree of frequency freedom independent of the LC of the tank circuit controlling the oscillator output.

Fig. 15 is a diagram of an oscillator having a reversed inductively reactive stabilized feed-back, and which oscillator may operate at the resonant frequency as well as at other frequencies of the controlling tank circuit, and Fig. 16 is a vector diagram relating to the operation of Fig. 15.

Fig. 17 is a diagram of an oscillator having a multiple or polyphase feed-back, one of which is reversed and one of which is direct. Under multiple feed-back operation, this oscillator may operate at the resonant frequency, as well as at other frequencies, of controlling tank circuit; and Fig. 18 is a vector diagram relating to the operation of Fig. 17.

Fig. 19 is a diagram of an oscillator having multiple feed-back; one feed-back being in phase with the plate voltage and having a magnitude proportional to the amplitude thereof, and one feed-back being in phase with the effective alternating plate current, and having a magnitude proportional to the amplitude thereof. Under multiple feed-back operation this oscillator may operate at the resonant frequency, as well as at other frequencies, of the controlling tank circuit, and Fig. 20 is a vector diagram relating to the operation of Fig. 19.

The outstanding literature of the prior art on

oscillators is replete with statements which indicate that the authors did not appreciate the operational theory as set forth by the applicant herein.

In Morecroft's book, *Principles of Radio Communication*, Wiley, 3rd edition, immediately after showing (beginning p. 575) that the grid voltage of an amplifier is in phase with the tube voltage and tube current only under conditions of having a pure resistance load, he, on p. 581, under the heading "General analysis of conditions necessary for self-excitation" (of oscillators), states: "The plate potential and the grid potential both undergo sinusoidal variations of potential in opposite phases, and that the relative magnitudes of these two potential variations can be properly adjusted for the tubes being used." Further, he bears out this statement in his Fig. 146, p. 591. This shows that he did not consider his preceding amplifier theory to apply to oscillator operation.

Prince and Vogdes in their book *Vacuum Tubes as Oscillation Generators*, published in 1929 by General Electric Company, devote their entire Chapter V to a treatment to show how the grid voltage can be made to operate in phase (opposite) with the plate voltage (on an inductive load) and thereby accomplishing what Morecroft set forth, as above related, to the operation of the grid voltage in opposite phase relation to the tube voltage. The statements made in their Chapter V show that the authors not only believed that these phase relations could be met (with an inductive load) but attempted to show how it could be accomplished.

Termian in his book *Radio Engineering*, McGraw-Hill, 1937, on page 356, under the heading "67. Frequency and frequency stability of generated oscillations," states: "The alternating current generated by the vacuum tube oscillator has a frequency such that the voltage which the oscillations apply to the grid of the tube is of exactly the proper phase to produce the oscillations that supply the required grid exciting voltage. This approximates the resonant frequency of the tuned circuit, but . . ." This statement must mean that the feed-back voltage is applied to the grid and that the resulting frequency approximates the resonant frequency of the "tuned circuit."

There are many other consistently expressed statements in the prior art literature such as, that an oscillator should operate at the natural period of the "tuned circuit" and related statements.

The applicant has discovered that:

(a) The operating frequency of a vacuum tube oscillator bears no necessary direct relation to the resonant frequency of the "tuned circuit."

(b) The natural period of a "tuned circuit" has no physical significance in a vacuum tube oscillator operation, except as it is related by definition to the figure of merit "Q" of the circuit.

(c) The grid voltage of the tube can be in opposite phase with the tube voltage and in phase with the tube current, only under conditions when the load is of an effectively resistive character.

(d) Under reactive loads of any character, the grid voltage, the tube voltage and the tube current are always all out of phase, one with the other.

(e) In oscillators, the grid voltage, the plate voltage and the plate current, have the same relations as given for amplifiers by Morecroft above, for inductive loads; but his amplifier analysis

does not apply to capacitive loads, and it is not seen how it correctly represents amplifier operation. That is, the character of the load fixes what the applicant terms the "grid operating voltage angle," which is the phase angle at which the grid must operate under the given load. For a reactive load this angle always lies in between the tube voltage and the tube current (plus or minus 180°).

(f) In an oscillator operating under a reactive load, any attempt to bring the phase of the grid voltage into a phase position different from its naturally assumed phase position, will cause a shift of oscillator frequency to a different frequency, which will cause the grid to assume a new proper out of phase position. The phase of the grid cannot be "corrected" on a reactive load to an arbitrary phase position.

(g) In a "tuned grid" reactively loaded oscillator, the generated frequency is determined by the frequency at which the grid tank circuit must operate to produce the required grid operating voltage angle (G. O. V. A.), between the tube voltage and the grid voltage, which may be leading or lagging depending upon the character of the load, and therefore the oscillator frequency may be below or above the resonant frequency of the grid tank circuit.

(h) The figure of merit "Q" of the tank circuit taken at resonance is not the operating Q of the circuit under reactive load, because the tank circuit does not operate at resonance under these conditions.

(i) The frequency stability of a "resistance stabilized" oscillator is not necessarily critical to the Q of the tank circuit, because the frequency stability is dependent upon the G. O. V. A. being maintained at the correct position with variation in the other circuit parameters, rather than the circuit dissipation.

(j) The variation in the tank circuit Q with different applied tank circuit voltages plays an important role in compensating for variation in the phase angle of the load current with different applied load voltages.

(k) The grid tank circuit in addition to functioning as an electrical "flywheel" for the circuit performs the important function of acting as an automatic G. O. V. A. adjuster.

(l) In a grid tank circuit oscillator having an inductively reactive plate load, inductance variations and/or variation in the Q of the load due to any cause whatever, and generally importantly to variations in the applied load voltage, cause changes in what the applicant terms the "load imposed current angle" (L. I. C. A.). For each change in the L. I. C. A., there is required a correct change in the G. O. V. A., to maintain the same oscillator operating frequency. Oscillator operating frequency stability is attained when the grid tank circuit (including grid current) automatically adjusts the G. O. V. A. to the correct value for the new L. I. C. A. at the correct operating frequency.

(m) In a resistance stabilized grid tank circuit oscillator having an inductively reactive plate load and a single feed-back circuit, a frequency is best stabilized against plate voltage variations, when the tank circuit is operating at a frequency considerably removed from the resonant value thereof.

(n) In a resistance stabilized grid tank circuit oscillator having an inductively reactive plate load, the most purely sinusoidal plate current is attained, when the tank circuit is operating at a

frequency considerably removed from the resonant value thereof.

(o) When an oscillator tank circuit has an intermittent drain imposed upon it, such as by intermittent grid current, tank circuit replenishment current in phase with the intermittent drain, distorts the sinusoidal character of the tank circuit voltage. Therefore an oscillator should not be operated with these two factors in phase, if sinusoidal operation is desired.

(p) Oscillators having inductively reactive plate loads, have an inherent tendency to produce sinusoidal currents and distorted tube voltages.

(q) Oscillators having condensively reactive plate loads, have an inherent tendency to produce distorted currents and sinusoidal tube voltages.

(r) Oscillators having condensively reactive plate loads when operating independently, are more difficult to stabilize than oscillators having inductively reactive plate loads, but are more sensitive to injected synchronizing currents, than the latter.

The above statements represent some important discovered facts upon which the present disclosure on which the illustrated embodiments of my invention depend.

In order to establish these discovered facts, the applicant will now treat the extra-conventional theory required to fully understand these statements.

To make it perfectly clear what the applicant means by the terms he uses herein, those terms which are not clearly fixed by universally accepted definitions or by universally accepted methods of experimental determination, will be treated in detail.

All of the discussions herein relating to frequency are made, for simplicity, with audio frequencies in mind, and the circuits have all been checked at 600 cycles or around this frequency as a center point. All discussions and determinations are made for operating current or voltage values, and are not made under artificial conditions. For instance, the Q of an iron-cored coil, not only depends upon the frequency, but also upon the voltage applied to it, so that the Q thereof made under conditions other than operating conditions, in general does not represent the operating Q. While some of such coils show a fairly constant inductance for increasing values of applied voltage or current, none possess a constant Q under such conditions. As an example, the inductance of a good iron-cored coil may not increase more than 0.1% for double applied voltage, whereas the Q of this coil may drop off 10% under the same conditions, and a good understanding of this fact is essential to a clear comprehension of the disclosure herein.

The method of measuring the phase angle, as used herein, of a tank circuit is illustrated in Fig. 1, by closing the switch 101. The generator line voltage is projected upon the oscilloscope screen, through the "A" input of the electronic switch, this image also, under the conditions of test, represents the tank circuit line current. The generator line voltage measurement, which is coupled to the "A" input of the electronic switch, is made by a "resistance drop" method, but across a small percentage of the total resistance used. Referring to the figure, the total resistance of the resistor 102, may be of the order of 1,000,000 ohms, and the resistance across the input of transformer 103, may be of the order of 10,000 ohms. Transformer 103, is preferably

an extremely high-fidelity extremely small type such as go by such trade names as, "ouncers," "inchers" and so forth, and should have an input impedance of the order of 1,000,000 ohms. The fidelity and phase angle of this coupling can always be checked, by use of the electronic switch projecting the transformer input and output voltages on the oscilloscope screen, simultaneously.

10 The form and phase position of the tank circuit voltage is projected superimposed upon the line voltage image upon the screen, by means of a special A₁ amplifier through input "B" of the electronic switch. With a precision oscilloscope, both wave amplitudes and phase displacement can be read with a good degree of accuracy. The special A₁ amplifier is constructed to have, at the frequencies employed, negligible phase difference between the input and output voltages, but without any necessarily high amplification. Such an amplifier may be constructed like a resistance-coupled-output design, but with the coupling capacitor having a relatively large capacity, and the output resistor having an ohmic value relatively very high to that of the plate resistor. Phase difference between the input and output can be tested by an electronic switch as related above.

By varying the frequency of the 40 pole generator, the familiar resonance curve, together with the related curve showing the phase angle between the tank circuit voltage and the tank circuit line current can be accurately determined under conditions representing operating voltage and current values. Such a set of curves is shown in Fig. 2, line C. These are the tank circuit voltage and current values and phase relations referred to herein.

There seems to be some confusion in the literature about the definition of Q and the method of determining it. It is usually defined as the ratio

$$\frac{L\omega}{R}$$

but it is sometimes also defined in the same text as the ratio

$$\frac{\text{volt amperes}}{\text{watts}}$$

(Radio Engineering Handbook, Henney, McGraw-Hill, 1941, pp. 132-3), which is not the same expression because the latter

$$= \sqrt{1 + \left(\frac{L\omega}{R}\right)^2}$$

55 The two expressions are only approximately equal for large values of Q.

For values of Q, where the phase angle between the voltage and current of the coil under test can be accurately determined by oscilloscopic indication, circuit of Fig. 1, is employed, by closing switch 101, and opening switch 104. The Q of the coil alone as defined by the ratio

$$\frac{L\omega}{R}$$

65 is the tangent of the angle between the operating voltage of the coil and the resulting current at the frequency employed. For values of Q above 10, corresponding to angles above 84° 10' (say above 85°), the value of the tangent increases so rapidly even with small angular increments, that accuracy in this range is difficult to attain by this method.

For these higher values of Q the applicant 70 measures the series capacity required to neutral-

ize the inductance of the coil at the operating voltage and frequency, by closing switch 101, opening switches 104 and 105, and measuring the capacity required of condenser 106, to produce resonance as indicated on the oscilloscope screen. From this capacity reading the value of L is computed and R is determined from the coil voltage. With the value of L known, Q is then determined for each or all values of voltage and frequency desired.

Where accuracy in a difference of phase angle is to be measured on the oscilloscope screen, which requires a fixed position of the traces of the wave forms measured independent of the amplitude of the synchronizing voltage, the applicant employs the method of synchronization disclosed in Patent No. 2,435,751.

The applicant herein distinguishes between the operation of a parallel resonance circuit under conditions of resonance operation, of natural period operation, and of equal reactance operation, as set forth by H. J. Boyland in Experimental Wireless for November 1927. However attention is called to the fact that this article contains formulas having typographical errors, which have to be corrected before using them.

Resonance operation of a parallel resonance circuit is determined by the applicant, by the method of zero-phase relation between the line voltage and line current as described above for series resonance determination.

The applicant determines natural period by use of the apparatus shown in Fig. 1. The method employs the use of the synchronous contactor which closes the generator supply voltage to the parallel resonance circuit for a period of time sufficiently long to permit the circuit to reach a steady state condition, and then disconnects the supply voltage and allows the circuit to oscillate at its free (natural) period long enough to count the number of natural periods as compared to a definite number of timing waves thrown on to the oscilloscope screen simultaneously, by means of the electronic switch. This method determines the natural period of the circuit under actual conditions of the operation.

Fig. 2, line A shows the appearance of the natural period being measured, and line B, shows the appearance of the timing wave. In practice lines A and B, are superimposed for convenience in counting and measuring. If variable frequency timing waves are available the two frequencies may be matched, if desired.

Equal reactance operation is obtained by first finding the capacity required for series resonance and then putting this amount of capacity in a parallel inductance-capacity circuit.

It is to be noted with this understanding of parallel inductance-capacity circuit operation, that the frequency of the natural period of the circuit is below the resonance frequency thereof, and the frequency at which equal reactance is obtained is below the frequency of the natural period, as illustrated along line C, Fig. 2, together with formulas showing how the angles between the voltage and current calculated, for the frequency employed.

Fig. 3 shows a push-pull oscillator having a resistance stabilized feed-back; the plate circuit has a center tapped resistor 301, one set of switches 302 and 303 for introducing parallel variable capacitors 304 and 305 across the ends of resistor 301, and a second set of switches 306 and 307 for introducing parallel variable capaci-

tor 308 across the central position of resistor 301. When switches 306 and 307 are open and switches 302 and 303 are closed the diagram will be referred to as circuit C. When switches 306 and 307 are closed and switches 302 and 303 are open the diagram will be referred to as circuit D.

Fig. 4 shows a push-pull oscillator having a resistance stabilized feed-back and pure resistive loading in the plate circuits. The diagram of this figure will be referred to as circuit E.

Fig. 5 shows a push-pull oscillator having a resistance stabilized feed-back; the plate circuit has a split inductor 501 with a center tapped resistor 502 inserted between the split coils. This part of the diagram will be referred to as circuit F. The figure also has a set of switches 503 and 504 for introducing parallel variable capacitor 505 across said split inductor; with switches 503 and 504 closed the figure will be referred to as circuit G.

The details of Figs. 6, 7 and 8 will be discussed under the operation of Figs. 3, 4 and 5, but before these operations are taken up, it is necessary to establish and define certain factors which enter into said operations, and which are explained in connection with Fig. 9.

In Fig. 9, the part of the diagram which lies entirely outside of the dotted areas H, I and J, constitutes a circuit identical with circuit F of Fig. 5 and will be referred to as circuit F₁, and while other circuits may be substituted in its place, the illustrated circuit suffices for purposes of illustration. The circuit F₁ of the figure is provided with a set of switches 901 and 902, which may be thrown to disconnect the grids of the triodes from the oscillatory system and connect the grids to a variable frequency center tapped source of variable alternating current 903. The figure shows and defines three methods of measurement which will be referred to hereinafter, namely:

Grid voltage measurement, which is employed to measure voltage values and phase positions, under conditions in which no line current and no appreciable line "de-setting" is permissible. This method is used also for obtaining the phase angle between the voltage and the current in a parallel oscillatory system, under similar conditions. The device within dotted area H is a special A₁ amplifier which is constructed to have negligible phase difference between the input and output voltages for the frequencies employed, but without any necessarily high amplification. Such an amplifier may be constructed like a resistance coupled output design, but with the coupling capacitor having a relatively large capacity and the output resistor having an ohmic value relatively very high to that of the plate resistor. Phase difference between the input and output can be tested by means of an "electronic switch" and a cathode ray oscilloscope.

Plate current measurements (the alternating current component thereof) are made by what may be called a "resistance drop" method. Referring to Fig. 9, the center tapped resistor 904 is a highly accurate non-inductive resistor which is left permanently in the circuit and has sufficient resistance to give a usable reading on high-resistance voltmeter V. M. The voltmeter resistance should be of the order of 100 times that of the resistor. Any direct current present in the resistor is prevented from entering the plate current measurement circuit by capacitor 905. The value of the current in the resistor is obviously determined by the voltmeter. For taking oscillo-

grams and phase angle measurements of the current in resistor 904, an extremely high-fidelity interstage transformer 906, is employed having an input impedance of the order of 100 times that of resistor 904. This arrangement should be checked for phase difference, because all transformers sold as high-fidelity types may not have a zero phase difference between the input and output for the frequency used.

Tube voltage measurements (the alternating current component thereof) are made by a "resistance drop" method but across a small percentage of the total resistance used, and if the total resistance used effects the circuit constants, the shunt resistance is either left in the circuit or an equivalent resistance is substituted, so that the operation of the circuit without the measuring device is the same as when it is in use. Referring to the circuit within the dotted area J, the total resistance points 907 and 908 may be of the order of 1,000,000 ohms, the effective resistance across the input of transformer 909 may be of the order of 10,000. Transformer 909 is preferably an extremely high-fidelity extremely small type such as go by such trade names as "ouncers," "inchers" and so forth, and should have an input impedance of the order of 1,000,000 ohms.

These combinations should always be checked for phase difference. With 100 plate A. C. volts good oscillograph deflections are obtained through an electronic switch, with the values given. With the circuit as connected in Fig. 9, the measurements are those of the circuit as an oscillator. With switches 901 and 902 thrown to connect independent A. C. source 903, the measurements are made on an amplifier and obviously phase angle measurements can be made on various parts of the circuit at any desired frequency.

Certain experimental facts which the applicant has discovered will be established on the operation of Figs. 3, 4 and 5, based upon measurements taken by the circuits explained in Fig. 9.

Referring to Fig. 4, if the voltage values and phase angle are taken of the parallel oscillatory circuit alone of circuit E, as a function of the applied frequency at a constant effective current, there is obtained the familiar resonance-voltage curve 701 and its phase angle curve 702, with reference to said current. If said oscillatory circuit is tuned to resonance at say X cycles independently and then put into circuit E, and the feed-back resistor properly adjusted, circuit E can be made to oscillate at X cycles or the resonant frequency of said oscillatory circuit.

However if the same oscillatory circuit with its X cycle resonant tuning and with the same adjustment of feed-back resistors, is substituted in circuit F and the proper measurements made, it will be found that circuit F does not oscillate at X cycles, but at some higher frequency 801, Fig. 8, and with a lower output with the same plate impedance, because it will be found that the grid voltage is lower.

Then if switches 503 and 504 are closed with low capacity adjustment of capacitor 505, it will be found that by increasing said capacity the frequency and grid voltage can be brought to the values of circuit E. Further adjustments of said capacity will lower the grid voltage.

Now if the same oscillatory circuit with its X cycle resonant tuning and with the same adjustment of feed-back resistors is substituted in either circuit C or D, say in circuit D, it will be

found that circuit D does not oscillate at X cycles, but at some lower frequency 601, Fig. 6, and with a lower output with the same plate impedance, because it will be found that the grid voltage is lower.

It will be found that other factors, like amount of feed-back resistance, Q of oscillatory circuit at the frequency and voltage employed, and other factors which are beyond the scope essential to this disclosure, also affect the oscillator frequency.

From the above tests it has been discovered that the circuits C, D, E, F and G, can be made to oscillate at the same frequency by employing different LC values in the parallel oscillatory circuits.

If the parallel oscillatory circuit of circuit F is set so that circuit F oscillates at any 600 cycles, it will be found that the oscillatory circuit voltage values and their phase relation to the tube voltage (oscillatory circuit current) as a function of the circuit frequency, is represented by Fig. 8, in which the frequency corresponding to the line 801, represents 600 cycles. Assume the phase lead shown to be say 60°, which is a practical value. This means that the grid voltage lags the tube voltage by 60° and that the oscillatory circuit is not operating at the resonant point, but in the steep region of the high-frequency side of the resonance curve.

By increasing the inductance of coil 501, that is by increasing the phase angle between the A. C. tube current and the A. C. tube voltage, the line 801 moves to the right and the operating frequency is increased, and by decreasing the inductance of coil 501, the operating frequency is decreased.

As it has been indicated, circuits C, D and G, can be adjusted so that the grid voltage leads the A. C. tube voltage at the operating frequency and say this frequency is 600 cycles and is represented by line 601, Fig. 6. Obviously increasing the shunt capacity of these circuits, decreases the frequency thereof and decreasing the capacity increases the frequency, within proper operating limits.

With these experimental phenomena disclosed, the applicant will establish a working theory for the making of oscillators in accordance with his invention, by the application of the analysis of amplifier operation.

In dealing with oscillators having an inductive load, use will be made of Morecroft's analysis of inductively loaded plate circuit amplifiers (in his above-referred to book, page 575), but the analysis given by him for capacitively loaded amplifiers is discarded, because it cannot be validly applied, as will be more fully pointed out hereinafter.

While the Morecroft analysis used herein is not a mathematically exact theory, even for amplifiers, it does provide a practical working theory, at least for audio frequencies, for the employment of the present invention, in the making of oscillators having inductive plate load.

A mathematically exact theory of oscillators made in accordance with the teachings of the present invention, as determined by setting up differential equations for the operation of the tube with its connected circuits, and obtaining solutions for them for a particular set of conditions, by numerical methods, leads to difficulties which prevent such solutions from being helpful in the making of oscillators.

However the development of the theory as

11

given herein, is sufficiently accurate to enable one skilled in the art, to make and use oscillators employing circuit elements having individually fixed circuit parameters, which elements when properly combined into oscillator circuits, result in oscillator operation at a predetermined frequency without circuit tuning, which is broadly new, to the best knowledge obtained by the applicant.

Referring to Fig. 10, this will be recognized by those skilled in the art, as a circuit which may be operated either as an amplifier or as an oscillator depending upon whether the switch 1001 is closed upon contact 1002 or upon 1003. Switch 1001 is first closed upon contact 1002 and amplifier operation is obtained from alternating voltage source 1004, and the resulting circuit is taken to operate in accordance with the assumed theory and analysis of Morecroft.

Fig. 11 is taken substantially from the Morecroft book and represents the approximate analysis of the above circuit on the assumptions made by him in arriving at his analysis. The vector notations are conventional and will be understood by those skilled in the art. For the basic assumptions and development of the theory, those skilled in the art are referred to the book. It is to be noted that the voltages and currents treated, are the alternating components of the voltages only.

In the operation of amplifiers, it is to be noted that with inductive plate load, the grid voltage E_g , does not and cannot be made to operate in phase with the tube voltage or in phase with the plate current. The grid voltage E_g (reversed in phase) must and does always lie, in phase relation, between the tube voltage E_p and tube current I_p . This is set forth as amplifier operation only and nowhere in the prior art does the applicant find this analysis developed for oscillator theory and further, all oscillator theory which has come to the attention of the applicant, is inconsistent with this analysis when applied to oscillator theory and in some cases entirely contrary thereto.

If the amplifier of Fig. 10 resulting from closing switch 1001 upon contact 1002, operates in accordance with Fig. 11, by changing the source of grid voltage will not change the necessary phase relation established between the tube voltage E_p , the grid voltage E_g , and the plate current I_p . Therefore if switch 1001, is closed upon contact 1003, forming an oscillator of the circuits of Fig. 10, these said phase relations must be maintained if the oscillator frequency is to be the same as that under amplifier operation.

Since the phase relation between the grid voltage E_g and the tube voltage E_p , must remain as shown in Fig. 11, the tank circuit 1005 of Fig. 10, must supply this difference of phase position of these two voltages. In the figure, the tank circuit current has the phase position of the tube voltage E_p and the tank circuit voltage must lag the tank circuit current, by the exact value which provides the grid voltage E_g , as called for in Fig. 11. This means that under inductive plate loading (with a single feed-back circuit containing only pure resistance), the grid tank circuit of the oscillator must operate, not at the resonant frequency of the tank circuit, but at the frequency which will cause the tank circuit to provide the grid operating voltage angle (G. O. V. A.) required by the load imposed current angle (L. I. C. A.). This means that an oscillator operating under inductive plate loading, must os-

12

cillate at a frequency higher than the resonant frequency of the tank circuit, as described as an experimental result in connection with Figs. 5 and 8.

It is entirely impractical as well as impossible to develop, in a patent application specification, this theory and analysis for all types of oscillator circuits, and all the discussion herein is directed to the types of circuits shown in Figs. 10, 3, 4, and 5. It is believed that disclosing a good teaching of the theory applied to these types of circuits, will provide those skilled in the art with sufficient knowledge of the subject to enable them to apply and embody the principles in other types of circuits.

It is obvious, to those skilled in the art, that under the above teaching the grid voltage phase angle cannot be "corrected" to any angle different from the G. O. V. A. which is determined 20 by the L. I. C. A., without changing the frequency of oscillations, and further under inductive plate loading, the G. O. V. A. cannot be brought into phase with the tube voltage or tube current under any conditions of operation.

Also the natural period of the tank circuit is not directly involved in the frequency of operation of such an oscillator, since the natural period is the period at which the tank circuit operates when "free," that is when it is not being driven. 30 whereas in oscillator operation the tank circuit is "driven" at the period which provides the necessary G. O. V. A., and there is no necessary direct relation between the two periods. The Q of a tank circuit influences the free period thereof 35 as a separated consideration, whereas the Q of a tank circuit as it functions in an operative element in an oscillator influences the difference between the free period and the driven period of the tank circuit of such an oscillator.

Referring to Figs. 5 and 8, the higher the Q of the tank circuit, the closer will be the operating frequency to the resonant frequency of the tank circuit. However good stable operation can be obtained with an operating Q (Q of tank circuit taken under operating conditions) as low as 45 5, and probably lower. Operating Q is not to be confused with Q taken at resonance frequency of the tank circuit, as this condition often indicates a higher value. The operating Q of the tank circuit in Fig. 10, must also include the grid losses.

Attention is directed to the fact that in an oscillator, having an inductive plate load, the tube reaction is in series with the load inductance and therefore the load inductance functions characteristically to reduce harmonics in the tube circuit current, any harmonics present appearing in the voltage. This accounts for the fact that such oscillators usually produce a tube current having a good sine wave-form, and a tube voltage having a considerable harmonic content in the wave-form thereof, mostly even harmonics introduced by the tube characteristics. It is to be borne in mind that in any circuit having the property of producing harmonics, they can be reduced or eliminated in the current or in the voltage of the circuit, but not in both. The inductively loaded oscillator reduces them in the current, and their reduction in capacitively load oscillators will be treated later on herein.

Now concerning this disclosed oscillator theory as applied to capacitively loaded oscillators, the amplifier analysis as given by Morecroft above, 75 cannot be validly applied, because his analysis,

as applied to amplifiers, as understood by the applicant is incomplete, faulty and incorrect.

Morecroft does not illustrate the amplifier circuit from which his oscillograms of an amplifier having a capacitive load were taken. His vector diagram of his capacitively loaded amplifier, is a diagram of a load circuit having only a resistance in series with a capacitance, corresponding with his vector diagram of his inductively loaded amplifier circuit, in which he does have only resistance in series with inductance. But the plate circuit of an amplifier (and of an oscillator as well) is a direct current circuit as well as an alternating current, and circuits having direct current conductivity requirement cannot have only resistance in series with capacitance. So that this vector diagram cannot represent amplifier operation and his oscillograms of amplifier operation having a capacitive load and zero resistance could not have been made with the two circuit elements in series.

The applicant discloses hereunder an amplifier circuit having a capacitive load, and a correct vector diagram therefor and how the analysis of these may be applied to oscillator operation.

Fig. 12 illustrates a circuit which like that of Fig. 10, may operate as an amplifier by closing switch 1201 upon contact 1202, or operate as an oscillator by closing switch 1201 upon contact 1203. The plate circuit of Fig. 12, possesses direct current conductivity and capacitive loading, as is well understood in the art.

This tube circuit differs from the series circuit of Fig. 10 in that in Fig. 10, the tube current has the same phase and wave-form, as the current in the resistance R and, as the current in the inductance L. In Fig. 12, this is not the case, the tube current is the vector sum of the current in the resistance branch and the current in the capacitance branch, of the parallel load of the tube. When dealing only with the alternating current components of the currents and voltages as heretofore premised herein, the same is true for the alternating current components thereof.

Referring to Fig. 12, switch 1201 is closed upon contact 1202, and the circuit operates as an amplifier from a grid voltage source 1204. Referring to Fig. 13, the angle of the load reaction is seen to be the reciprocal of the value for the series circuit, given by Morecroft above, and the angles between the grid voltage and tube voltage and tube current are very different values from those given by him for capacitive loads (see his page 579).

Referring to Fig. 12, the switch 1201, is closed upon contact 1203, under which condition the resultant circuit operates as an oscillator and the tank circuit 1205, provides the G. O. V. A. as determined by the vector diagram of Fig. 13.

The corresponding circuits of Fig. 3 operate similarly and an illustrative graph of the G. O. V. A. with the corresponding tube voltage angles are shown in Fig. 6.

Referring to Fig. 12, it will be seen, that the tank circuit current has the phase of the tube voltage E_p , and referring to Fig. 13, that the tank circuit voltage must lead the tank circuit current to provide the G. O. V. A., necessary for oscillator operation. This explains the experimentally discovered operation of Fig. 3, as illustrated in the graph of Fig. 6, in that the oscillator operates at a frequency lower than the resonant frequency of the tank circuit.

It will be seen in capacitively loaded oscillators that the tube reaction is partly in series with the

load condenser and therefore the load condenser functions characteristically to induce harmonics in the tube circuit to appear in the tube current, and therefore reduce them in the tube voltage. This accounts for the fact that such oscillators usually produce a tube voltage having a good sine wave-form, and a tube current having considerable harmonic content in the wave-form thereof, mostly even harmonics introduced by the tube characteristics.

If the oscillator of Fig. 12 has switch 1206 opened, all the angles of the diagram of Fig. 13 disappear and all voltages and current are thrown into phase. This explains the operation of the oscillator of Fig. 4, as experimentally determined by the graphs shown in Fig. 7.

With the experimental disclosures and explanatory operating theory developed above, and with the aid of the measurement directions given herein, the applicant now shows how his discoveries can be embodied in some other new and useful devices.

Fig. 14 shows an oscillator in which the tank circuit has a fixed LC, and it is caused to operate over a wide range of different frequencies, by interposing, in the oscillator feed-back circuit, a feed-back phase shifting means.

The circuit enclosed within the dotted area J, is an oscillator of the F type shown in Fig. 5, when switches 1401 and 1402 are closed respectively upon contacts 1403 and 1404. As a specific example, switches 1401 and 1402 are closed, the tank circuit 1405 and the feed-back resistors are adjusted to give stable operation at 600 cycles.

The G. O. V. A. is determined by the method illustrated in Fig. 9. This oscillator with the same feed-back current and the same G. O. V. A. will oscillate at 600 cycles regardless of the source of the feed-back current. Also this oscillator operates at other frequencies for other phase positions of the G. O. V. A. as shown experimentally in Fig. 8 and analytically in Fig. 11, so that interposing a phase shifting in the feed-back circuit of the oscillator enclosed within the dotted area J, will result in an adjustable frequency oscillator having a fixed LC in the tank circuit.

Referring back to Fig. 14, the circuit enclosed within the dotted area K, is an amplifier having a resistance-capacitance output and a phase shifting means in the input circuit. In the form illustrated this phase shifting device is a parallel inductance-capacitance circuit having an adjustable LC, but any other suitable phase shifting means may be used.

Switches 1401 and 1402, are opened and switches 1409 and 1410 are closed respectively upon contacts 1411 and 1412. The condenser 1413 is selected so that at its middle point, the phase angle of the output of the amplifier is exactly in phase with the oscillator tube voltage, then the feed-back angle to the oscillator tank circuit through the amplifier, is the same as when switches 1401 and 1402 were closed, hence the oscillator operates at 600 cycles, as it did originally. Adjustment of condenser 1413, causes the oscillator to run faster or slower, depending upon whether the G. O. V. A. is increased or decreased, as illustrated in Fig. 8.

It has been stated (F. E. Terman, Resistance stabilized oscillators, Electronics, July 1933) that in oscillators which he describes, which are type F oscillators, the feed-back resistance must be non-inductive. The applicant now shows how with his discovery and invention, oscillators of this type can be constructed with more inductance

than resistance in the feed-back circuit, and operate with good stability.

Fig. 15 shows an oscillator embodying the applicant's discovery and invention which has a large inductance in the feed-back circuit. The oscillator is constructed for 600 cycle operation as follows:

First the circuit has the feed-back circuit open and the tank circuit removed. The G. O. V. A. for the L. I. C. A. determined by the method shown in Fig. 9. The tank circuit is separately adjusted to resonance by the method shown in Fig. 1. The tank circuit is then properly connected in the grid circuit as shown in Fig. 15. The amount of feed-back current is calculated from the tubes and circuit employed, then the inductance of reactors 1502 and 1503, and the resistance of resistors 1504 and 1505, are calculated from the well known vector relation shown in Fig. 16, to provide the correct G. O. V. A. and when the feed-back circuit is connected up as shown, the oscillator operates at 600 cycles, or very close thereto, depending upon the accuracy of the work performed. Thus is produced an inductively loaded oscillator, with a tank current operating at resonance, and with largely inductive impedances in the feed-back circuit. When properly constructed, the oscillator shows good frequency stability.

With the teaching given in connection with Fig. 15, further disclosure can be made with reference to Fig. 14. In the disclosure given for the construction of oscillators in accordance with Fig. 14, directions were given to set the tank circuit 1405, for proper operation at the given frequency with feed-back resistors 1406 and 1407 in circuit. Attention was directed to the fact that the circuit enclosed within dotted area K, constitutes a phase shifting circuit replacing these feed-back resistors under conditions of adjustable frequency operation.

With reference to Fig. 15, it was shown that the tank circuit 1501, can be set to resonance at the frequency of operation, when the feed-back circuit has a proper phase shifting means inserted into it. Since circuit enclosed in dotted area K is a phase shifting means, the tank circuit 1405 of Fig. 14 can be set also to the resonance at the frequency of operation, and the proper phase shift of the feed-back circuit can be obtained by adjustment of condenser 1413, or of the LC of the circuit including condenser 1413. Further, since it is seen that the G. O. V. A. required for any L. I. C. A. is a vector result of the phase angle of the tank circuit 1405, and of the relative phase angle of the feed-back circuit, the LC of the tank circuit 1405 can have a wide range of different values for the same oscillator operating frequency, if means is employed in the feed-back circuit to cause the proper phase angle feed-back current to the tank circuit for the operating frequency desired.

The applicant will now give directions for the embodiment of his discovery and invention in oscillators by the employment of polyphase feed-back circuits. Referring to Fig. 17, there is shown therein an oscillator having tank circuit 1701 with a fixable LC, and a conventional reversed feed-back circuit comprising condensers 1702 and 1703, in series with resistors 1704 and 1705. This circuit supplies feed-back current in phase with the tube voltage, the vector representation of which is identified in the diagram of Fig. 18.

The required G. O. V. A. is further shown in the figure. If the tank circuit 1701, is to work

at resonance, the tank circuit feed-back current must be in phase with the G. O. V. A. This is accomplished in this embodiment by a direct feed-back circuit, comprising, in Fig. 17, resistors 5 1704 and 1705, in series with condensers 1706 and 1707, which provide a second feed-back current having an out of phase position of such magnitude and phase difference relative to the reversed feed-back circuit to cause the desired magnitude of 10 feed-back current and the proper G. O. V. A. to cause the desired frequency of operation of the oscillator.

While only two phases of feed-back current is shown, it will be appreciated by those skilled 15 in the art of polyphase currents, that any number of properly chosen phases may be employed to produce a single phase current of a desired phase relation to the reference phase of the circuit.

In view of the foregoing disclosures, it will be 20 seen that the LC of the tank circuit 1701, does not have to be set to the resonant operating frequency of the oscillator, but may be set at different other LC values for the same operating 25 frequency of the oscillator, if the polyphase feed-back circuits are adjusted to provide the required G. O. V. A. for the load employed at the frequency of operation.

A further method and structure, for supplying 30 polyphase feed-back circuits to the tank circuit of an oscillator, are shown in Fig. 19, in which the tank circuit 1901, has a conventional feed-back circuit, comprising condensers 1902 and 1903, in series with resistors 1904 and 1905, supplying feed-back current in phase (reversed) 35 with the tube voltage to the tank circuit, shown in vector representation in Fig. 20, by the vector identification.

The oscillator of Fig. 19, has a current transformer within the dotted area L. The voltage 40 drop across the input of this transformer is small as compared to the total load voltage, and the secondary thereof is generally shunted by a condenser 1906, and has the feed-back resistors 1907 and 1908, as a load therefor. This current 45 transformer is constructed and adjusted such that the feed-back load current is in phase with, but not necessarily so, the alternating current component of the plate load current. The phase 50 position of this second phase of feed-back current is identified in the vector diagram of Fig. 20, and its vector composition to give the required G. O. V. A., for the desired operation is conventionally analyzed in the Fig. 20.

It will be appreciated by those skilled in the 55 art that, in general, the operation of the tank circuit at its resonance frequency, provides a more economical use of the LC of that circuit and therefore results in greater apparatus efficiency, and this is an important item since the tank circuit usually constituted an expensive element in the cost of oscillators.

All of the circuits disclosed herein have been 60 actually constructed and operated as described herein at 600 cycles as a frequency center point and therefore any differences of opinion as to alternate explanations of the operation does not effect the validity of the disclosures.

Having taught herein, the nature of my discovery and invention, other and further embodiments will be obvious to those skilled in the art.

What I claim is:

1. In an electrical oscillation system including an electron discharge tube having a plate, a control grid and a cathode; a load circuit, a discharge control circuit including said grid, said cathode

17

and a tank circuit, and a feed-back circuit from said load circuit to said tank circuit including electrical-circuit phase-shifting means varying the operating frequency of said system.

2. In an electrical oscillation system including an electron discharge tube having a plate, a control grid and a cathode; a load circuit including a reactive member, a cathode-grid circuit including a tank circuit set to an operating voltage-current phase-difference having an angular value different from the grid operating voltage angle required for the load imposed current angle of said system, and a feed-back circuit from said load circuit to said tank circuit including phase shifting circuit means compensating for said different value.

3. In an electrical oscillation system including an electron discharge tube having a plate, a control grid and a cathode; a load circuit, a cathode-grid circuit including a tank circuit, and a feed-back circuit from said load circuit to said tank circuit including electronic-tube phase-shifting means varying the operating frequency of said system by angular variation of the grid operating voltage angle.

4. In an electrical oscillation system including an electron discharge tube having a plate, a control grid and a cathode; a load circuit, a cathode-grid circuit including a tank circuit, and a feed-back circuit from said load circuit to said tank circuit including an electronic tube amplifier having a variable LC tank circuit in the cathode-grid circuit thereof.

18

5. In an electrical oscillation system including an electron discharge tube having a plate, a control grid and a cathode; a load circuit including an inductive reactor, a cathode-grid circuit including a tank circuit set to resonance at the operating frequency of said system, and a feed-back circuit from said load circuit to said tank circuit including phase shifting circuit means causing current fed to said tank circuit to flow at a phase angle equal to the grid operating voltage angle required for said operating frequency of said system.

10 MONTFORD MORRISON.
